UNITED STATES PATENT OFFICE.

STANLEY M. LAWSON, OF CINCINNATI, OHIO.

DESIGN FOR A FURNITURE-FOOT.

43,822.

Specification for Design.

Patented Apr. 8, 1913.

Application filed November 1, 1912. Serial No. 729,156. Term of patent 7 years.

To all whom it may concern:

Be it known that I, STANLEY M. LAWSON, a citizen of the United States, and residing at Cincinnati, Hamilton county, State of Ohio, have invented a certain new, original, and ornamental Design for a Furniture-Foot, reference being had to the accompanying drawing, which shows my design in side elevation.

I claim—
The ornamental design for a furniture foot, as shown.

STANLEY M. LAWSON.

Witnesses:

C. SPENGEL,
T. LE BEAU.
